US0D1098624S

(12) United States Design Patent (10) Patent No.: US D1,098,624 S
(45) Date of Patent: * Oct. 14, 2025

(54) PET NAIL GRINDER

(71) Applicant: Shenzhen Diben Technology Co., LTD, Shenzhen (CN)

(72) Inventor: Chenglin Luo, luoding (CN)

(73) Assignee: Shenzhen Diben Technology Co., LTD, Shenzhen (CN)

() Term: 15 Years

(21) Appl. No.: 29/883,785

(22) Filed: Feb. 3, 2023

(51) LOC (15) Cl. 30-05

(52) U.S. Cl.

CLAIM

The ornamental design for a pet nail grinder, as shown and described.

DESCRIPTION

FIG. 1 is a first perspective view of a pet nail grinder showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the pet nail grinder that form no part of the claimed design.

1 Claim, 8 Drawing Sheets
